UNITED STATES PATENT OFFICE

DAVID S. SWARTHOUT AND PAUL H. SMYTH, JR., OF EVANSTON, ILLINOIS

AUTOMATIC PHONOGRAPHIC APPARATUS

Application filed May 23, 1928. Serial No. 279,952.

This invention relates to means for automatically and selectively feeding a series of phonographic records to the playing position, and in controlling the operation of the turntable to automatically begin and conclude the playing of a record, and to there-after restore the record to the idle position in preparation for the delivery, playing and restoration of a number of records compos-
10 ing the group or series.

The machine may be adjusted to play in succession the entire group or series of records, or any fraction thereof, or it may be ad-
15 justed to selectively play one or more records from the group.

The invention is designed with a view of greatly simplifying the mechanism required in the automatic delivery and restoration of the records to and from the playing position, and is also designed with a view of promptly
20 disengaging and restoring the record imme-
diately after the same has been played, which playing period may be of varying length in different records.

In order to effect the prompt restoration of the record to idle position, independently of the length of time for playing, it is necessary that the means for disengaging and restoring the record shall be under the control of the tone arm, which swings inwardly across the face of the record as the playing progresses; and in the present case the disengagement and restoration are effected as soon as the tone arm reaches its innermost position at
30 the terminus of the record line, regardless of the number of rotations of the turntable, and regardless of the time consumed in playing. This method of control is, therefore, much superior to one which automatically disen-
35 gages and restores the record in any definite time relation to other portions of the mech-
anism, since such arrangement necessitates that all records remain in the playing position during a definite interval, which must
40 be the maximum required in the playing of the longest record in the series.

Further objects and details of the invention will appear from a description thereof, in conjunction with the accompanying draw-
50 ings, wherein,—

Figure 1 is a front elevational view of the mechanism forming the subject matter of the invention;

Fig. 2 is a side elevational view of the mechanism;

Fig. 3 is an enlarged longitudinal vertical sectional view corresponding substantially to the line 3—3 of Fig. 2, and showing the mechanism in position before the turntable is elevated to playing position;

Fig. 4 is a longitudinal sectional view similar to Fig. 3, showing the positions of the mechanism after the turntable has been ele-
60 vated to playing position;

Fig. 5 is a horizontal sectional view taken through the housing, and showing in plan the operating mechanism of the device, the section corresponding substantially to the line 5—5 of Fig. 3;

Fig. 6 is a transverse sectional view through the housing, corresponding sub-
70 stantially to the line 6—6 of Fig. 3, portions of the housing being broken away;

Fig. 7 is fragmentary enlarged top plan view of that portion of the mechanism in-
75 cluding the tone arm and record, portions of the construction being broken away;

Fig. 8 is an enlarged horizontal sectional view taken through the base portion of the tone arm, and corresponding substantially to the line 8—8 of Fig. 9;

Fig. 9 is a fragmentary vertical sectional view taken through the tone arm mecha-
85 nism;

Fig. 10 is an enlarged detailed view of an operating lever associated with the tone arm for restoring the mechanism to initial position after a complete cycle of operations;

Fig. 11 is an enlarged detailed view show-
90 ing the cam surface carried by the tone arm lever;

Fig. 12 is an enlarged detailed view of a portion of the selecting mechanism;

Fig. 13 is a transverse vertical sectional view corresponding substantially to the line 13—13 of Fig. 12;

Fig. 14 is an enlarged detailed view of a portion of the selecting mechanism; and

Fig. 15 is a top plan view of one of the de-
100 livery arms, showing the manner of mount.

ing, the standard upon which the arm is mounted being shown in horizontal section, the full line position of the arm corresponding to playing position, while the dotted fragment indicates the inoperative position of the delivery arm.

The record feeding mechanism is mounted upon a base 10 provided at one end with an upstanding arcuate standard 11 provided in its inner edge with a plurality of notches 12, each of which constitutes the bearing for a swinging feeding arm 13, which at its outer end carries a record supporting ring 14 which is of a size to support and feed a standard record. The record supporting ring 14 is notched to afford a ledge 15 upon which the rim of the record is supported. The arm 13 at its opposite end terminates in an outwardly extending finger 16 which is preferably slightly offset with respect to the arm 13, and the arm is pivoted within the arcuate standard by a pin 17 which passes through one of the journal notches in the inner edge of the standard.

Each of the arms composing the entire group is pivoted on a center which is angularly disposed with respect to the next succeeding one, the pivots for the entire group being in arcuate relation to one another, conforming to the curvature of the supporting standard, so that each of the arms, when actuated, will swing inwardly to the center or operating position without interference from any of the others.

The operating position is that occupied by the turntable 18 which is mounted upon a vertically movable rotatable spindle 19, so that when an individual record is swung to operating position above the turntable the turntable may be lifted with appropriate mechanism presently to be described, by lifting the record out of and above the position in which it is supported by the feeding arm which is the playing position for the record.

The spindle 19 is journaled through a head 20 at the end of an arm 21, which merges into the base of the standard, being integrally formed therewith; and the spindle has fixedly mounted thereon a large driving pulley wheel 22 which carries a belt 23 passing over a drive wheel 24 on a motor 25 which is running to constantly drive the turntable.

The spindle 19 carries a clutch collar 26 associated with a driving clutch element 27 which coacts with a driven clutch element 28, which clutch element 28 is fast with a worm 29 slidably mounted upon the lower end of the spindle 19, which is slidably mounted within a journaled bracket 30. When the spindle is in a lowered position, the clutch elements are in mesh with one another to effect rotation of the worm and impart a driving movement to mechanisms presently to be described; but when the spindle is elevated to lift the turntable into playing po-

sition, the clutch elements will be disconnected, so that there will be no transmission of motion during the playing period.

Each of the swinging arms is actuated by means of a stiff flexible wire connection 31, 70 which at its outer end is connected to the end of the finger 16 and passes through an aperture 32 in the arcuate standard and into a flexible tube 33, the end of which is fixedly socketed into the aperture 32 which permits movement of the wire through the tube. By drawing on any selected wire of the series, a corresponding arm can be swung from its idle position inwardly to the playing position immediately above the turntable, at 80 which point it will be stopped by contact with a stop finger 34 which is mounted upon the bracket arm 21, and which limits the movement of the arm when it arrives at a position immediately above the turntable.

All of the wires 31 are led around behind the group of record feeding arms, and each wire makes connection with one of a series of blocks 350, slidably mounted between rods 351. Each block pivotally carries a draw rod 35, the forward end of which is provided with a heel 36, and the rear end of which is pressed upwardly by a spring 352. In the present instance, ten operating arms are shown and ten draw rods are provided, and in order to actuate any selected one of the ten draw rods, the parts are arranged so that the entire group of heels 36 will stand in aligned relation when the feeding arms are in idle position, and in this position each of the ten heels will lie immediately above a groove or channel 37 formed in the end of a slide plate 38. When any selected heel is thrown downwardly it will register with the groove, so that thereafter a movement of the slide plate 38 will carry with it whichever of the draw rods has been elevated into engaging position. The slide plate thus becomes a common actuating mechanism for any selected one of the arms.

In order to effect a successive lifting of the heels, the following mechanism is provided: The cam drum 39 is provided immediately above the forward ends of the group of ten draw rods, which drum, as shown, is ribbed 115 to afford intermediate grooves which receive the ends of the draw rods 35, and each groove is provided with a notch 40, the notches of succeeding grooves being spirally arranged, so that it requires one complete rotation of the drum to successively actuate all of the ten draw bars. The arrangement is such that the rear or heeled end of the draw bar will, at a predetermined point in the rotation of the cam drum, be lifted into engagement 120 with the common draw plate, and such engagement of the respective draw bars will follow in predetermined sequence. The cam drum is actuated one step at a time through the action of a ten-toothed ratchet wheel 45 130

which is rigidly associated with the drum, and rotation is imparted to the ratchet wheel by means of a dog 46 which is pivoted at its upper end to a lever 47 pivoted to a bracket 5 48, a spring 49 being provided to hold the lever in advance position. The lower end 50 of the lever is adapted to be swung forwardly by engagement with the worm 29. The worm wheel is mounted upon a shaft 53 upon which 10 is freely mounted a cam 54 which lies adjacent to the face of the worm wheel. The cam drum 39 may be manually rotated independently of the automatic mechanism by means of a knob 390 affixed to the shaft carrying the drum.

The cam 54 is of truly circular formation throughout approximately half of its periphery, and is elevated on the side 55. At the extremity of elevation, the cam is shouldered to afford a hook 56 adapted to engage with and pick up a pin 57 extending outwardly from the sides of the worm wheel, so that with the worm wheel moving in a clockwise direction the cam will be caught 20 at a predetermined period in the rotation and rotated with the worm wheel. The cam coacts with a clutch lever arm 58 which is pivoted to a bracket 59, the free end of the clutch lever arm being bifurcated to engage 25 the clutch collar 26, so that when the high point on the cam arrives in proper position to engage the clutch lever arm, the arm will be lifted, which in turn lifts the clutch collar and with it the turntable, which is 30 thus elevated into playing position. It will be observed, however, that the first effect of this lifting movement will be to separate the clutch elements and thus stop the driving of the worm wheel through the worm 59, 35 and in these circumstances it is necessary to provide means for continuing the movement of the cam which will be required to completely elevate the turntable to playing position. This additional movement is imparted 40 through the action of springs 60, which are secured to a cross head 61 on a rod 62 which is slidably mounted in a pivoted guide member 63. The cross head is pivoted to the cam by a pin 64 so disposed that when the cam 45 has been positively moved past the dead center position the tension of the springs will cause a further movement of the cam, which will effect the final lifting of the turntable standard.

55 The extreme end of the arm 58 embraces a vertical draw rod 65 provided with a head 66 so disposed that when the free end of the arm 58 has been ultimately lifted to its final position by the high point of the cam, the 60 arm will engage the head 66 and actuate a bell crank lever 67 pivoted to a bracket 68. The lower arm of the bell crank engages the end of a stop pin 69 which is slidably entered through the journal 30 for the turntable spindle, the arrangement being such

that when the turntable spindle has been lifted to its highest position it will lie above the pin 69, so that the latter is thrust inwardly beneath the end of the spindle to hold the spindle elevated, while the arm 59 70 falls back upon the low portion of the cam. This holds the turntable in elevated position during the entire playing period.

The tone arm 70 is swivelly mounted upon the frame in such position that when the record is lifted by the elevation of the turntable, the needle of the tone arm will engage the outermost portion of the record line and travel inwardly in the usual manner during the playing period. A lever 660 is provided, 75 carried by and movable with the tone arm 70, which has a cam 670 adapted to engage the head 66 and force it downwardly gradually until the playing of the record is completed, at which time the pin 69 is retracted 80 and the turntable lowered through gravity, releasing the record from the needle. When this occurs, the tone arm will be free and will be swung outwardly by a spring 700 to its normal position in preparation for the playing of the next succeeding record.

In order to actuate the slide plate 38, the plate at its lower end is provided with a slotted heel 71 which coacts with a lever 72 provided with a point 73 engaged within 85 the slot in the heel. The upper end of the lever is pivoted to a bracket 74, and the lever is actuated by means of a link 75 pivoted to the worm wheel and adapted to be moved back and forth thereby. The arrangement 90 is such that when the worm wheel is being actuated by the worm in clutched relation with the turntable spindle, the draw plate will be moved either by being drawn back or thrust forward, as the case may be, to 95 actuate the record feeding arm during this interval, while during the playing period the clutch elements will be separated so that the draw plate will stand in stationary relation during the playing interval.

The motor can be set in operation, if desired, by means of gun-actuated mechanism of any well known character, which forms no part of the present invention, and with the motor in operation, and with the turntable 100 lowered to its normal or non-playing position, the clutch elements will be engaged, and this will cause the feeding of the worm wheel in a clockwise direction. The worm and worm wheel are so related that the worm 105 will travel throughout one rotation during a complete playing period, thereby performing a complete cycle of operation in the desired sequence.

As the worm wheel rotates it will retract 110 the common draw plate 38, thereby drawing with it whichever of the draw bars is for the time being engaged therewith, through the control of the cam drum. The retraction of the draw bar will pull with it the operating 115

wire connected therewith, and this will actuate the particular record feeding arm to be played for the time being. As soon as the record feeding arm has been swung to feeding position, the continued operation of the worm wheel will bring the pin 57 into position to pick up the cam and carry it around, and this movement of the cam will elevate the clutch control arm 58, thereby breaking the clutch and holding the slide plate in its retracted position during the playing interval. With the breaking of the clutch, the cam 54 will be swung around by the tension of the springs 60, and during the movement of the cam the turntable will be elevated to its ultimate position, which lifts the record away from the ring support on the arm and brings it into engagement with the needle.

The turntable, being constantly rotated by direct connection with the motor, will cause the record to rotate during the playing interval, until the continued in-swinging of the tone arm brings it into a position to depress the vertical draw rod 65 through suitable connections, which depression of the draw rod retracts the pin 69 which supports the foot of the turntable spindle, thereby allowing the spindle to fall by gravity. This effects a reclutching of the clutch elements and initiates the return portion of the cycle of the worm wheel, during which movement the common draw plate 38 will be thrust forwardly, imparting a thrust to be engaged therewith, and this thrust movement of the wire will swing back and restore the record feeding arm with the record carried thereby to its idle position.

During the restoring movement of the record arm, the pin 57 on the worm wheel will engage the lower end of the lever 47 and impart a thrust thereto, which through the dog 46 effects a one-tenth rotation of the cam drum, and thereby causes the next succeeding draw bar to engage with the common draw plate in preparation for the playing of the next record.

We claim:

1. In mechanism of the class described, the combination of a turntable, a spindle carrying the turntable and mounted for rotation and vertical reciprocation, a plurality of superposed record feeding arms each separately pivoted at a point distant from the turntable the pivoted axes progressively varying with respect to the operative plane of the turntable and each axis being properly oriented to permit the associated record feeding arm to swing inwardly to a position immediately above the turntable to bring its record into concentric relation to the turntable, means for raising and lowering the turntable spindle and means for rotating the same, connections associated with each of the record feeding arms for swinging a selected arm to playing position and thereafter re-

storing the arm to idle position, the means for raising and lowering the turntable and for swinging the arms being associated to first swing a selected arm inwardly to playing position, thereafter to elevate the turntable to deposit the record thereon, thereafter to lower the turntable, and finally to swing back the record feeding arm to idle position.

2. In mechanism of the class described, the combination of a turntable, a spindle carrying the turntable and mounted for rotation and vertical reciprocation, a plurality of superposed record feeding arms each separately pivoted at a point distant from the turntable the pivoted axes progressively varying with respect to the operative plane of the turntable and each axis being properly oriented to permit the associated record feeding arm to swing inwardly to a position immediately above the turntable to bring its record into concentric relation to the turntable, means for raising and lowering the turntable spindle and means for rotating the same, connections associated with each of the record feeding arms for swinging a selected arm to playing position and thereafter restoring the arm to idle position, means for actuating said arm swinging means in successive progression, the means for raising and lowering the turntable and for swinging the arms being associated to first swing a selected arm inwardly to playing position, thereafter to elevate the turntable to deposit the record thereon, thereafter to lower the turntable, and finally to swing back the record feeding arm to idle position.

3. In mechanism of the class described, the combination of a turntable, a spindle carrying the turntable and mounted for rotation and vertical reciprocation, a plurality of superposed record feeding arms each separately pivoted at a point distant from the turntable the pivoted axes progressively varying with respect to the operative plane of the turntable and each axis being properly oriented to permit the associated record feeding arm to swing inwardly to a position immediately above the turntable to bring its record into concentric relation to the turntable, means for raising and lowering the turntable spindle and means for rotating the same, connections associated with each of the record feeding arms for swinging a selected arm to playing position and thereafter restoring the arm to idle position, means for actuating said arm swinging means in successive progression, the means for raising and lowering the turntable and for swinging the arms being associated to first swing a selected arm inwardly to playing position, thereafter to elevate the turntable to deposit the record thereon, thereafter to lower the turntable, and finally to swing back the record feeding arm to idle position, and thereafter swing in the next succeeding record feeding arm to

playing position in the same sequence of operations.

4. In mechanism of the class described, the combination of a turntable, a spindle carrying the turntable, means for rotating the spindle, clutch elements carried by said spindle and adapted to be engaged when the turntable is lowered, driving elements adapted to be actuated when the clutch elements are engaged, means actuated by said driving elements for initially lifting the spindle to disengage the clutch elements, spring means adapted thereafter to impart a final upward movement to the turntable to bring the turntable to playing position, and record feeding means adapted to deliver a record into position to be deposited upon the turntable when the turntable is elevated.

5. In mechanism of the class described, the combination with a turntable, of means for presenting a plurality of records individually to said turntable, said means including: a support, and a plurality of superposed arms pivotally mounted on said support, each arm having a record holding portion, said arms being individually swingable each on an individually computed axis to present the record holding means to a common position with respect to said turntable.

6. In mechanism of the character described, the combination with a turntable, of means for presenting a plurality of records individually to said turntable, said means including: a support, a plurality of superposed arms pivotally mounted on said support, each arm having a record holding portion, said arms being individually swingable each on an individually computed axis to present the record holding means to a common position with respect to said turntable, and means for selectively operating said arms, including an extension on each arm, and a flexible member connected to said extension and adapted to be moved in opposite directions.

7. In mechanism of the character described, the combination with a turntable, of actuating means; a plurality of individually movable elements adapted to separately present a record to a common position with respect to said turntable; and selecting means including: a plurality of bars, and a slide plate, said slide plate being connected with said actuating means, and said bars being normally urged in a direction to engage said slide plate, a roller co-operating with said bars to maintain the same out of engagement with said slide plate, said roller being provided with a plurality of recesses arranged in different positions for permitting individual connection of said bars with said slide plate when said roller is rotating, and connections between said bars and said record carrying elements.

8. In mechanism of the character de-

scribed, the combination with a turntable, of actuating means; a plurality of individually movable elements adapted to separately present a record to a common position with respect to said turntable; and selecting means including: a plurality of bars, and a slide plate, said slide plate being connected with said actuating means, and said bars being normally urged in a direction to engage said slide plate, a roller co-operating with said bars to maintain the same out of engagement with said slide plate, said roller being provided with a plurality of recesses arranged in different positions for permitting individual connection of said bars with said slide plate when said roller is rotating; connections between said bars and said record carrying elements; and means for automatically rotating said roller.

9. In mechanism of the character described, the combination with a turntable having an axially movable spindle, of driving means; clutch elements co-operating with said spindle and driving means; a device for disconnecting said clutch elements and partially elevating said turntable, said device including yieldable means for further elevating said turntable when the drive is disconnected; a latch for maintaining the turntable in elevated position; and a lever for tripping said latch to permit lowering of said turntable.

10. In mechanism of the character described, the combination with a turntable having an axially movable spindle; a tone arm adapted to co-operate with said turntable in one position and being spaced therefrom in another position; a plurality of pivoted arms, each having a record carrying portion and adapted to individually present a record in a common position above said turntable, drive means, and clutch elements between said drive means and the turntable spindle; a device for elevating and lowering said turntable, including a cam operated arm for disconnecting said clutch elements and lifting said turntable, and including a latch automatically engageable for supporting said turntable in elevated position; selecting means, including a plurality of bars and a slide plate, said slide plate being connected to said drive means, said bars being normally urged toward engagement with said slide plate; a roller normally holding said bars out of engagement with said slide plate, said roller being provided with a plurality of recesses adapted to be engaged by said bars when said roller is rotated, for causing individual engagement of said bars with said slide plate; means for operating said roller step by step through a connection with the drive means; and a lever operable by movement of said tone arm for tripping said latch to permit lowering of said turntable and re-
